PAPER MAKING METHOD AND MACHINE

Harry A. Chuse, Madison, Wis.

Application October 6, 1934, Serial No. 747,175

9 Claims. (Cl. 92—38)

This invention, relating to paper making methods and machines, is concerned particularly with the procedure and equipment employed subsequent to the making of the wet sheet; the objects of the invention being to provide an improved method and means for drying paper in the process of manufacture in a continuous sheet, and to provide an improved method and means for the entire procedure to which the paper sheet is subjected after its removal from the medium on which it is formed. In a general sense the invention may be regarded as providing a novel paper making method and machine as a whole, though not involving novelty with respect to the making of the wet sheet.

The process of making paper in a continuous sheet involves progressive removal of water from the formed sheet by the action of a succession of agencies. On a Fourdrinier paper making machine, for example, the removal of water from the paper sheet begins while the sheet is still on the making wire, much water being removed by draining through the wire, some water being dispensed from the sheet by the action of the flat suction boxes across which the wire slides, and an additional percentage of water being forced from the sheet by the action of the suction couch roll at the delivery end of the wire. However, after the sheet has formed with accompanying drainage of its surplus water by gravity and table roll action, the water contained in the sheet is so tenaciously held that only a limited reduction of the water content of the sheet can be accomplished by the action of the flat suction boxes and the suction couch roll. Ordinarily when the wet sheet leaves the making wire, or after it has passed the suction couch roll, it will be only about 20% or less dry, or in other words will contain 80% or more of water, depending upon the thickness of the sheet, the stock from which it is formed, the speed at which it is made and the efficiency of the flat suction boxes and suction couch roll to reduce the moisture content of the particular sheet made at the particular speed.

Thus the wet paper sheet delivered from a Fourdrinier making wire or other medium on which the sheet is formed is composed of a relatively large proportion of water and a relatively small proportion of paper material, by weight, the percentage of water contained in the sheet being, as above stated, ordinarily about 80% or more. This great amount of water or most of it must be removed from the sheet by subsequent operations to reduce the sheet to the relatively low moisture content desired for the calendering

operation or in the finished paper. Ordinarily for the calendering operation the sheet should contain only from about 5% to 10% moisture, depending upon the percentage of moisture desired in the finished product.

For the removal of water from the wet sheet between the stages of its delivery from the making wire or medium on which it is formed and the calendering operation, the conventional method which for many years has been and is now employed involves the expressing or squeezing out of a certain proportion of the water from the wet sheet by the action of a series of presses, which requires the carrying of the wet sheet on moisture absorbing press felts through the first and second presses and sometimes through the third press; and the drying of the sheet after pressing by carrying the sheet around or in contact with a series of ordinary driers consisting of revolving steam heated cylinders which heat the paper and cause its drying by evaporation, the evaporated moisture being carried off by ventilation.

As the paper cannot be produced any faster than it can be delivered in sufficiently dry state for the calendering operation, the capacity of ordinary drying equipment required for a paper making machine will depend upon the speed at which the paper made on such machine is formed and delivered to the driers, and upon the amount of water contained in the sheet when it is delivered to the driers, wherefore it has been considered advisable to remove by pressing or by pressing and supplemental agencies as much water as is practicable to remove from the sheet in this manner before the sheet is delivered to the driers. The modern high speed Fourdrinier paper making machine of conventional character has therefore elaborate press and press felt equipment, and extensive drying equipment to provide the drying capacity required for drying the paper as fast as it is delivered from the Fourdrinier making wire or other medium on which the sheet is formed.

Now the press section of a paper making machine, besides comprising elaborate and cumbersome equipment occupying a considerable amount of space, has always been and is a troublesome part of the machinery, due among other causes to the difficulty of running the paper through the presses without breakage or without injuring the paper or by crushing effects. The speed at which paper can be produced on conventional machines is primarily limited not only by the rate at which it can be formed on the

table but also by the speed at which it can be run through the presses without injury and then dried for calendering. Modern improvements in the Fourdrinier including particularly the suction couch roll, and the use of long press felts of good quality and other improvements in connection with the presses including particularly suction press rolls, have made it possible to produce ordinary news print paper at speeds ranging up to 1,000 ft. per minute and over. Nevertheless the press section of the Fourdrinier remains a troublesome factor and is believed to impose a speed limitation without which it might be possible in the future to attain substantially higher speeds in paper production than are now feasible.

Moreover the press section of the paper machine requires constant attention, the maintenance of the press felts in cleansed condition, and the frequent removal and replacement of press felts, with consequent expense. Furthermore the amount of water which can be removed from the sheet by pressing, or by the use of a series of heavy presses in conjunction with press felts, is quite limited. Ordinarily the sheet after it leaves the third or last press of the paper making machine will contain about 65% or more of water, which large amount of water except the low percentage desired to be retained in the finished product must be removed by drying, requiring consequent extensive drying equipment where the conventional method of drying is employed.

The present invention contemplates a radical departure from conventional paper making methods and machines with respect both to the drying and drying equipment in the ordinary sense and the entire procedure between the stages of delivery of the wet sheet from the Fourdrinier making wire or other medium on which it is formed and the calendering of the sheet. The invention provides for drying the sheet in such manner as not only to give requisite drying capacity for a high speed paper making machine with much less extensive equipment than if ordinary driers were used, but also in such manner as to dry the sheet advantageously and economically without preliminarily removing water from the sheet by pressing, and yet with substantially less extensive equipment than the ordinary drying equipment required after the sheet has been subjected to the usual pressing operation. Thus the invention contemplates omission of the step of removing water from the sheet by pressing, thereby eliminating the elaborate, cumbersome and costly press and press felt equipment with all of its difficulties and objections. On the other hand, pressing the sheet while sufficiently moist to be compacted and smoothed by the pressing is desirable, and the invention contemplates retaining a limited pressing operation preferably performed by a single pair of press rolls operating on the bare paper sheet at a stage of the drying operation after the sheet is too dry for expressing moisture or for injury by the pressing operation. Preferably the pressing is done when the sheet is about from 70 to 80% dry, or in other words when the moisture content of the sheet is reduced to from about 20% to 30%, it having been found most advantageous from the standpoint of fiber strength to conduct the pressing operation when the sheet has been reduced to such a relatively low moisture content.

Thus the invention in one aspect contemplates the drying of the paper principally or mainly

before pressing, and the reduction of the pressing operation to a compacting and smoothing operation at an intermediate stage in the drying operation, preferably by the use of a single press, after the sheet is of too low a moisture content for the squeezing out of water or for injuring the sheet by such operation, and preferably when the sheet is reduced to a moisture content of from about 20% to 30%. However it is to be understood that the drying methods and equipment provided by the present invention, or the features of the invention in connection with the said drying methods and equipment, are susceptible of general utility in the paper making industry, or in other words that the drying methods and equipment embodying the present invention or features thereof are intended to replace present methods of drying in paper manufacture, whether with or without preliminary removal of water from the paper sheet by pressing or by pressing and other agencies before delivery of the sheet to said drying equipment.

For the paper drying process, the invention utilizes extensively the property of air to absorb moisture with which it is brought into intimate contact. According to the invention, the drying process involves successively forcing large volumes of air through the paper sheet, under conditions promoting vaporization of the moisture in the sheet and the absorption and carrying off of the moisture by the air passing therethrough. In carrying out the invention the paper sheet delivered from the making wire may be entrained about a series of revolving closely perforated cylinders, the air being forced through the paper and the perforations in the cylinders. The forcing of the air through the paper may be induced by external air pressure or by suction within the cylinders or by a combination of both. As the most expedient and practicable system, suction within the cylinders is employed. The said cylinders may consist of the perforated shells of suction rolls of appropriate construction to provide extensive suction areas to be sealed by the paper sheet entrained about the cylinders. For convenience such cylinders are herein referred to as suction driers to distinguish from the ordinary driers which merely heat the paper sheet to cause evaporation of moisture.

The process of drying the paper by forcing air therethrough can be hastened and can be accomplished with a smaller use of air than would otherwise be needed by heating the air considerably and heating the paper sheet occasionally or in alternation with the forcing of the heated air therethrough. The process of evaporation by air circulating in intimate contact with the moisture in the sheet has a cooling effect notwithstanding that the air forced through the sheet is in a heated state. It is therefore highly advantageous to heat the paper sheet occasionally or in alternation with the forcing of heated air therethrough by carrying the sheet around ordinary driers, thereby preserving proper heat balance for full moisture saturation of the heated air passing through the sheet. It will be understood that the volume of heated air which passes through the paper sheet on any suction drier absorbs and carries off a certain proportion of moisture in the sheet, but with a cooling effect as above noted, which without succeeding heating of the sheet would reduce the moisture absorbing effect of the volume of heated air passed through the sheet on the next suction drier. By carrying the sheet around

ordinary driers in alternation with the suction driers, the desired heat balance between the sheet and the heated air to be forced therethrough is restored. The heat imparted to the sheet by the 5 ordinary driers promotes rapid vaporization of the moisture in the sheet and full moisture saturation of the air successively passed through the sheet.

On ordinary paper machines the ideal temperature of the paper is from five to ten degrees below the temperature of the steam heated driers, and it remains constant. By a system of drying the paper by carrying it alternately around ordinary driers and suction driers, the 10 paper leaves a heated drier at about the same temperature as in ordinary practice but under the evaporation process in the succeeding suction drier or driers it may cool 100° or more by the time it reaches the next reheating drier; 15 hence the average temperature range will produce a flow of heat from the heated drier to the paper of five or six times the rate possible with the old method.

With ordinary methods of drying, there is 20 considerable difficulty in drying the paper to the narrow limit desired by the trade. If the paper contains too much moisture it will not print well. If delivered too dry, there is a loss in desired weight and the calendering is not so effective 25 nor will the paper print as easily as if properly calendered. The invention contemplates therefore drying the paper to a higher degree than is desired for calendering, and then conditioning the paper for calendering by forcing moisture laden air through the paper just before it is 30 calendered.

Other method and mechanical features of the invention will be apparent from the following description of certain methods and machines embodying the invention, reference being had to the 35 accompanying drawings in which:

Fig. 1 is a diagrammatic view of a paper making machine of one practicable construction embodying and for practicing a method embodying 40 the invention.

Fig. 2 is an enlarged view of the first section of the drying equipment of said machine.

Fig. 3 is an enlarged view of the second section of said drying equipment.

Fig. 4 is an enlarged view of the third section of said drying equipment.

Fig. 5 is a cross section through one of the drying sections and condensing apparatus associated therewith.

Fig. 6 is a diagrammatic view of a modified machine embodying features of the invention.

Fig. 7 is an enlarged view of the second section of the drying equipment of the machine shown in Fig. 6.

Fig. 8 is a longitudinal section of a suction drier.

Fig. 9 is a view partly in end elevation and partly in cross section of said suction drier.

Fig. 10 is an end view of blocking off means of a suction drier.

Fig. 11 is an enlarged detail view of the blocking off means shown in Fig. 9.

The specific machine selected for illustration will now be particularly described, it being understood that the following description thereof 50 is to be taken as explanatory and not as limiting the invention which is hereinafter set forth in the claims.

In Fig. 1, the reference numeral 1 designates the making wire of a high speed Fourdrinier paper 55 making machine. The wet section of the ma-

chine, represented by the making wire, will be understood as including all approved equipment necessary or desirable in connection with the making of the wet sheet, including liquid stock supplying apparatus, the breast roll, table rolls, deckles, dandy roll, flat suction boxes and other accessories employed in modern high speed Fourdriniers. The making wire at its delivery end is entrained on a suction couch roll 2 whereby the wet paper sheet which forms on the making wire, 10 after submission to the action of the flat suction boxes, is subjected over the suction couch roll to a constant high tension vacuum action with a resultant consolidating and moisture reducing effect such that the paper sheet is made in a relative firm and intact condition, though containing, as before indicated, usually about 80 per cent or more of water. The wet sheet made on the machine is designated by the numeral 3.

The machine represented in Fig. 1 comprises 20 the Fourdrinier wet section, herein represented by the making wire, drying equipment which in this instance is in three sections, a single press 4 located between the second and third sections of the drying equipment, and calenders 5; there being no press section in the ordinary sense of equipment for pressing water from the paper sheet preparatory to drying.

The drying equipment, shown more clearly in Figs. 2, 3, and 4, comprises in this instance a series of driers numbered 6 to 29, inclusive, including suction driers numbered 7, 9, 11, 13, 15, 17, 19, 21, 23, 24, 26, 27, 28, and ordinary driers numbered 6, 8, 10, 12, 14, 16, 18, 20, 22, 25. The paper sheet is carried successively around the driers 30 in the order in which they are numbered. With the particular arrangement shown, the paper sheet is carried alternately around suction and ordinary driers in the first and second sections of the drier equipment (Figs. 2 and 3), and in the third section is carried alternately around ordinary and suction driers and then around a succession of suction driers 26, 27, 28 and then around a conditioning unit 29 which is similar to the suction driers but is employed in this instance for forcing moisture laden air to the dry paper sheet preparatory to calendering.

Each suction drier comprises a revolving cylinder in the form of a closely perforated metal shell 30 having closed ends and containing a large perforated suction pipe 31 in connection with suitable vacuum pumping apparatus (not shown) whereby to maintain sufficient suction or vacuum action within the cylinder to cause the forcing of air from the exterior of the cylinder through the paper sheet entrained thereon. The major portion of the cylindric area of such suction drier is sealed or covered by the paper sheet passing around or about the drier, while the small segment which is not covered by the paper sheet is blocked off by means indicated at 32 in Figs. 2 to 4 to prevent the ingress of air through the perforated area not covered by the sheet, whereby to cause all air drawn into the cylinder to pass through the paper. Each cylinder may be covered or jacketed by a wire cloth jacket 33 (Figs. 8 and 9) to avoid any possibility of water marking or other marking of the sheet by the perforated pattern of the shell.

As before stated, the drying system in the 70 illustrated machine is arranged in three sections respectively shown in Figs. 2, 3, and 4. Each drying section comprises a number of said suction driers and of said ordinary driers, together with suitable carrying means for carrying the 75

paper sheet successively around the driers or with carrying and holding means for carrying the sheet around certain of the driers and for holding them in cooperative relation with certain of the other driers, which carrying means or carrying and holding means are represented by the drier felts hereinafter referred to, though in some instances and particularly in the manufacture of paper heavier and denser than ordinary newsprint the drier felts or certain of them may be replaced by wire cloth aprons. The driers of each section are enclosed by a housing in connection with a source of warm or preheated air, and contain air drying or air heating equipment, such for example as steam heating coils. All steam heating coils in the several drier sections are designated by the numeral 34.

The first drier section (Fig. 2) which receives the wet paper sheet from the Fourdrinier making wire, and in which the most elementary stage of the drying is performed, comprises the ordinary driers 6, 8, 10, 12 and suction driers 7, 9, 11, 13 arranged in alternation therewith, and the coating felts 35 and 36 which receive the paper sheet between them and carry the sheet successively around the said driers; the return runs of said felts being guided by the guide rolls 37 and the felts being tensioned by the adjustable take-up rolls 38. This section of the drying equipment is enclosed by the drier housing 40 having a warm air inlet 41. Within the housing are the steam coils 34, shown arranged in proximity to and substantially surrounding the respective areas of the suction driers which are entrained by the felts and paper sheet carried thereby. As shown, the wet paper sheet 3 delivered from the Fourdrinier making wire is deposited upon the felt 35 which carries the sheet through the guide opening 42 into the housing and travels around the guide roll 39 whereby the sheet is brought into contact with the coating felt 36 and the two felts carrying the sheet between them travel successively around the driers. The sheet passes from the last drier 13 under the guide roll 43 and out from the housing for delivery to the next section of the drying equipment. In the particular construction shown in Fig. 2, the housing opening through which the paper sheet emerges is substantially closed by the drier 13 and guide roll 43. Guide openings in the housing for the return run of the lower felt 37 are indicated at 44.

With the illustrative arrangement of the felts 35 and 36 of the first drier section, one of said felts is inside the paper and the other felt is outside as the paper is carried around the driers. This arrangement is advantageous for the first stage of the drying paper sheet in the relatively wet condition in which it is received from the Fourdrinier making wire. It protects the freshly made wet paper sheet from the sudden heat of the first driers, thus protecting the sheet from tendency to burn to the driers. It passes the paper sheet from drier to drier, will deliver all broke for removal as hereinafter described, and protects the paper sheet on the suction driers, preventing any marking of the paper at the suction holes or by the wire screen cloth jacketing the suction driers.

In passing through the first drier, the wet paper sheet is heated both by ordinary driers or steam heated drying cylinders 6, 8, 10, 12, and by the heat radiated from the steam heating coils 34 and by the heat of the air in the drier housing, causing vaporization of the moisture in the sheet, 75 which is absorbed and carried off by the heated

air passing through the sheet as it is carried around the suction driers, so that the moisture reducing action of the suction driers is very largely supplemented by evaporating action in addition to that effected by the passing of large volumes of air successively through the sheet, besides which the desired heat balance is maintained to afford maximum absorption capacity of the air passing through the sheet. A large proportion of the water is removed in this first drier section, whereby the moisture content of the sheet is reduced below that obtainable by use of the ordinary elaborate press and press felt equipment, so that the sheet delivered from said first drier section will be substantially dryer than when delivered to the drying equipment of a paper making machine having conventional press and drier equipment.

The second drier section (Fig. 3) comprises the suction driers 15, 17, 19, 21 and ordinary driers 14, 16, 18, 20 arranged in alternation with said suction driers, a felt 45 which travels successively around all of the driers, and a felt 46 which cooperates with the suction driers to assist in passing the paper sheet and in holding the sheet to said suction driers, said felt 46 being arranged for short arc contact with the sheet on said suction driers. The housing for the second drier section is designated by the numeral 47, and the warm air inlet by the numeral 48. Guide openings for the felt 45 are indicated at 49. Guide rolls at the paper inlet and outlet ends of the drier are indicated at 50 and 51; other guide rolls for the felts at 52, and adjustable take-up rolls for tensioning the felts at 53. Within the drier housing 47 are steam coils 34 arranged in association with the suction driers in the same manner as already described.

The paper sheet delivered from the first drier section is deposited upon the felt 45 and follows the same route as said felt through the second drier section, passing with the felt into the drier housing 47 and over the guide roll 50 and then successively around all the driers and then passing with said felt under the guide roll 51 and out from the drier housing.

With the arrangement of felts employed in the second drier section, the paper sheet passing through said section is inside the felt 45 as it goes around the ordinary driers 14, 16, 18, 20, 50 so that the paper sheet is carried in direct contact with said ordinary driers or steam heated cylinders as is now desirable for efficient heating of and rapid evaporation of moisture from the partly dried sheet. On the suction driers 15, 17, 19, 21 the felt 45 is on the inside of the paper sheet as before to protect the paper. The small contact of the other felt 46 presents less obstruction for the passage of air through the paper sheet than does the ordinary arrangement.

As the sheet is delivered to the second drier section in a partially dried state and without having undergone the compressive action of presses, the forcing of heated air through the sheet is very effective in the second drier section, and by this action in alternation with the heating of the sheet on steam heated drying cylinders or ordinary driers the sheet in passing through said second section is further dried in an advantageous manner, and may be rendered as dry as or dryer than after having passed through three-fourths of ordinary drying equipment.

In both the first and second drier sections, the felts must have a very beneficial effect in drying the paper sheet by absorbing much of its

moisture and surrendering it to the warm air through which the felts are continually passing. This feature is especially strong in the first drier section. The two felts can hardly fail to reach the paper except in dry and hot condition. These two dry and hot felts pressed one on each side of the wet sheet of paper will instantly take up a large percentage of its moisture which will be removed from the felts by evaporation on the 10 return runs of the felts.

The function of the first and second drier sections is to dry the paper sufficiently to bring it to an advantageous state of dryness for pressing. As before indicated, it is desirable to avoid 15 pressing while the paper sheet is relatively wet, and to press the paper for compacting and smoothing effect after its moisture content has been reduced to from about 30% to almost 20%. Probably the most advantageous moisture content of the paper sheet for pressing is about or 20 near to 20%. It is contemplated therefore that the capacity of the first and second drier sections shall be such that the paper sheet delivered from the second drier shall be between 25 70% and 80% dry, preferably about or near 80% dry. After delivery from the second drier section, the paper sheet runs through the single press 4 for compacting and smoothing, and is then delivered to the third drier section for further drying preparatory to calendering.

The third drier section comprises the ordinary driers 22 and 25, suction driers 23 and 24 in alternation therewith, additional suction driers 26, 27, 28 and conditioning unit 29, a felt 54 arranged to cooperate with the lower tier of driers 22, 24, 26, 28, and a short felt 55 arranged to cooperate with the one ordinary drier 25 of the upper tier of driers. The felt 54 is held in cooperative relation to the lower tier of driers by 40 the guide rolls 56, while the return run of said felt is engaged by guide rolls 57 and the adjustable take-up roll 58 for tensioning the felt. Guide rolls for the short felt 54 are indicated at 59.

45 The housing for the third drier section is numbered 60, and its warm air inlet 61. The paper sheet enters said housing through the guide opening 62 and travels successively around the driers and thence around the conditioning unit 29, and then under the guide roll 63 and to the calenders 5. Within the drier housing 60 are steam heating coils 34 arranged as already mentioned in association with the suction driers. Some of the steam coils in the housing 60 are 55 also arranged in proximity to the surfaces of the ordinary driers 22 and 25 which are engaged by the paper sheet and felts.

In the third drier section the paper sheet is covered by the felt 54 on the ordinary drier 22 60 and by the short felt 55 on the ordinary drier 25, but is carried around the suction driers free of felts except for the short contacts of the felt 54 on the suction driers 24, 26, 28. As the paper sheet passes through the third drier section, the 65 drying of the sheet is continued, first by the alternate action of ordinary driers and suction driers, and then by the continued forcing of heated air through the sheet on the suction driers 26, 27, 28, whereby the paper sheet is rendered 70 sufficiently dry for calendering or, in this instance, drier than desired for calendering.

Because of the difficulty of drying paper to the narrow limits desired by the paper trade, the 75 illustrative machine is designed to dry the paper continuously too dry and then to condition the

paper for calendering by passing moisture laden air through the sheet, utilizing for this purpose the roll 29 which is similar to the suction driers. As shown in Fig. 4, the conditioning unit 29 is contained in a separate compartment of the 5 drier housing, which separate compartment is formed by the partition 64. Warm moist air enters said compartment through the inlet openings 65 and is drawn through the paper sheet on the unit 29, conditioning the paper for calendering. Water coils 66 may be arranged in said compartment for cooling the warm moist air entering the same to a predetermined temperature which may be kept constant by a suitable temperature control (not shown) which admits just 10 enough cooling water to do this. The air having a constant temperature will have a constant capacity for moisture as any excess of moisture in the entering air will be condensed and carried out by the drip collector 67. Since paper has a 15 great affinity for moisture if subjected to moisture laden air, it will draw moisture from the saturated air which is passed through it. This absorption will depend upon the relative humidity of the air, kept constant as above indicated, 20 and the time of exposure. The time of exposure is kept constant as it is the time required for the paper to pass over the suction unit 29. Hence, paper at or near the desired final moisture content will be tempered to very close limits by 25 properly governing the temperature of the saturated air passed through it. The amount of absorption of moist air by the paper could also be controlled in other ways as for example by 30 the method hereinafter explained with reference 35 to Figs. 6 and 7.

In threading the paper sheet through the drying apparatus, the sheet is carried through the first drier section by the coacting belts 35 and 36. It may be threaded through the second drier section by means of an ordinary Shehan carrier (not shown). However it is possible to thread the paper sheet through the second section by means of the felt 45 with the assistance of air jets presently to be referred to and with the assistance of the top felt 46. For threading the sheet through the third drier section, a Shehan carrier (not shown) is employed.

45 Provision for recovery of broke from any section of the drying apparatus will now be described. In case of a break in the paper sheet in the first section, the broken sheet will be carried by the coacting felts 35 and 36 to the suction drier 13, from which the sheet may be blown off by air discharged from a blower or other suitable source from a series of pipes 68 located within said suction drier. The broken sheet may be caught on the broke catcher 69 and discharged through an opening normally 50 closed by the door 70. In the second drier section (Fig. 3), a number of air nozzles 71 are arranged to discharge jets of air against the sheet in directions to hold it against the suction driers as the sheet passes thereto from the ordinary driers. Hence any broke will be carried around an ordinary drier by the felt 45, and thence to the next suction drier by the said felt with the assistance of the air jets discharged at 55 71, and over said suction drier by the top felt 46 cooperating with the lower felt; and after the broken sheet passes from the felt 46 the suction within the suction drier will cause the sheet to hug to the felt 45 and be carried thereby to the next ordinary drier. Thus broke will be de- 60

70 75

livered in the second drier section to the last drier 21, from which it may be blown off by air blowing from pipes 72. The broken sheet may be caught on the broke catcher 73 and discharged through an opening normally closed by the door 74. In the third drier section, nozzles 75 are arranged to discharge jets of air toward the receiving sides of the several suction driers. Additional nozzles 76 near the off-bearing side of the drier 22 are arranged to discharge air downwardly. The several suction driers are provided with air pipes 77 for blowing the paper sheet from the off-bearing sides of said driers. The suction driers 24, 26, 28 in the lower tier of driers are provided with additional air pipes 78 arranged to blow air from the receiving sides of said driers. If a break occurs on the first drier 22, the broke will be blown from the off-bearing side of said drier by the nozzles and will be carried by the felt 54 under the lower tier of driers, the air discharged by the pipes 78 preventing the broke from ascending the receiving side of any of the driers 24, 26, 28. If the break occurs on the suction drier 23, the air jets discharged by the nozzles 75 associated with this drier will hold the sheet to its receiving side and the suction within the drier will hold it to its off-bearing side, and the broke will be blown off by the air blowing from pipes 77 in said drier and will be held to the next drier 24 by the air jets discharged from nozzles 75 associated therewith. Thus the broke will be caught on the felt 54, and will be prevented from ascending the receiving side of any of the suction driers 24, 26, 28 by the discharge of air from pipes 78. If broke occurs at any subsequent stage in the third drier section, the mode of handling it will be obvious. Nozzles 79 near the off-bearing side of the drier 28 are arranged to discharge air downwardly to assist in discharging broke over the slide 80 through an opening normally closed by the door 81.

The blow-off pipes 60 in the last drier of the first drier section, the corresponding blow-off pipes 72 in the last drier of the second section, the nozzles 71 of said second section, the nozzles 75, 76 and 79 of the third section, and the blow-off pipes 77 and 78 of the suction driers of said last section, are used respectively only to assist in carrying the sheet when it is being threaded through the machine, or to carry broke. These several nozzles and blow-off pipes may be connected through separate valve-controlled connections (not shown) with any suitable source of compressed air, so that the air can be turned on for use when and if required, and shut off during the normal use of the machine.

The sheet metal casings or housings containing the drier sections are constructed with numerous doors to permit access to the driers, felts and paper. As shown in Figs. 2 to 4, the drier housings are constructed with various doors or hinge sections in the top, ends and bottom. Various other doors or hinge sections are provided in the sides of the housings.

It is desirable to provide for recovery and utilization of the large amount of heat that is contained in the air and moisture discharged from the various suction driers, and particularly from those of the first drier section which removes from the wet paper sheet by evaporation water that is ordinarily pressed out and which uses a relatively large amount of heat. Reference will now be made to provision for such heat recovery.

As shown in Fig. 5, the suction driers of the first drier section are connected to vacuum-pumping apparatus (not shown) through a counterflow heat interchanger comprising a casing 82 having inlet and outlet chambers 83 and 84 connected by a series of condenser tubes 85. The inlet chamber 83 is connected by the piping 86 with the suction pipes in the suction driers, and the outlet chamber 84 is connected by the pipe 87 with the vacuum-pumping apparatus. The tubes 85 extend through an intermediate chamber 88 through which is drawn the air that is supplied to the first drier section. The air to be so supplied is drawn from the fresh air duct 89 and discharges through the outlet duct 90 either direct to the housing of the first drier section or to an intermediate apparatus for further pre-heating the air. The fresh air thus drawn through the heat interchanger condenses about 90% of the moisture in the air discharged from the suction driers, thus heating such air and recovering a large amount of heat that would otherwise be wasted; while the moisture condensed in the tubes 85 may be drawn off through the hot water outlet 91 and may be used again as hot as desired in the white water supplied for making the pulp solution to be used on the wet section of the machine or may be used as boiler feed water.

Each section of the drier may be equipped with similar heat recovery apparatus, or the entire series of suction driers may be connected with similar apparatus of sufficiently large capacity to recover the heat in the air and moisture discharged from all the suction driers.

The air supplied to the drier sections is thus preheated by the heat discharged from said sections, with accompanying condensation of the water discharged from said sections. The condensed hot water can be used as boiler feed water, white water or for heating purposes. Thus the actual consumption of heat in the drying process is materially reduced. The preheated air supplied to the drier sections may be further preheated by passing over steam coils supplied with exhaust steam from the engine or bleeder turbine. In the drier sections the air is further heated by steam coils 34, in which some live steam may advantageously be used, though it is intended to use principally exhaust steam in the coils 34 as well as in the ordinary driers or steam heated drying cylinders.

The hot moist air supplied to the conditioning unit 29 may be derived from any suitable source; for example the suction pipe of an individual suction drier in the first drier section may be connected with the inlets 65 of the chamber in which the conditioning unit 29 is situated, so that the conditioning unit will draw the supply of moist air from such drier.

The drying equipment described with reference to Figs. 1 to 5 is in accordance with a construction and arrangement of drying equipment which has been designed for a machine for high speed production of newsprint paper. It will be understood that said equipment may be variously modified as to the number of drying sections, the number and arrangement of suction driers and ordinary driers in the respective sections, and as to various details, to suit various different conditions and requirements. It is contemplated for example that wires may be used in place of some or all of the felts, that some of the felts may be omitted, or others added, and that drying systems embodying features of the invention may

omit all felts or wires for carrying or holding the paper sheet.

The wet section of the illustrative machine represented by the Fourdrinier making wire 1 typifies any suitable wet section. The wire 1 typifies any suitable medium on which the wet paper sheet is formed or any suitable carrying medium to which the sheet is transferred from the surface on which it is formed.

10 Reference will now be made to Figs. 6 and 7, which represent a machine embodying features of the invention and adapted for conditions in which the sheet of paper or paper material can be dried for pressing with less drying capacity than

15 that of the machine first described. The machine of Figs. 6 and 7 is in accordance with a construction designed especially for manufacture of bulky or loose paper such as blotter and the like. It would also be suitable for drying pulp sheets 20 if the press were omitted.

The wet section of the machine shown in Figs. 6 and 7 is represented by a Fourdrinier making wire 100 entrained at its delivery end on a suction couch roll 101. The machine has two drier sections 25 102 and 103, a press 104 between the two drier sections, and calenders 105.

The first drier section 102 comprises a series of suction driers 106 and cooperating felts or wires 107 and 108 by and between which the paper sheet 109 is carried successively around said suction driers. Said drier section is enclosed by a housing similar to the housing previously described, and contains steam heating coils 110. The sheet in passing through said section is dried 35 by the forcing of the heated air through the sheet, together with the drying effected by the hot felts and the heat radiated to the sheet from the heating coils.

The second drier section 103 comprises ordinary driers 111, suction driers 112, a felt 113 which cooperates with the lower tier of driers, and a short top felt 114 cooperating with the one ordinary drier in the upper tier. This second drier section is substantially similar in all respects to the last 45 drier section of the machine shown in Fig. 1, except that in the machine of Figs. 6 and 7 a different means is provided for conditioning the sheet for calendering. In the machine of Figs. 6 and 7, the paper sheet passes successively around the 50 driers and from the last drier passes around guide rolls 115 and 116. Moist air for conditioning the sheet is drawn through the sheet on a segment of the last suction drier. The moist air is drawn from a suitable source of supply into the inlet 55 chamber 117 and flows from said chamber through the passage 118 to the hood 119 from which the moist air is drawn through the sheet by the suction in the last suction drier. The passage 118 is controlled by the rotary valve 120 operated by the lever arm 121. The lever arm 121 is pivotally connected to and suspended from link 123, the last mentioned link being pivoted to the drier housing at 124. Link 122 is pivotally connected to the long arm 125 of a bell crank 60 65 lever which is fulcrumed at 126 and the short arm 127 of which carries an adjustably mounted weight 128. Another weight 129 is adjustably mounted on the arm 125 of the bell crank lever. The arm 125 of the bell crank lever carries a roller 70 75 130 held against the paper sheet between the guide rollers 115 and 116. The weights 128 and 129 are so adjusted that the roller 130 bears against the paper sheet. When the paper sheet is taut the parts are in the position shown in Fig. 7, the valve 120 being open. If the paper

sheet receives too much moisture, the sheet will stretch between the rollers 115 and 116, allowing the roller to move toward the right and close or partially close the rotary valve 120, thereby regulating the amount of moist air that can be drawn through the sheet from the hood 119.

Reference will now be made to Figs. 8 and 9, illustrating one practicable construction for a suction drier. As before stated, the reference numeral 30 designates the perforated shell of the 10 drier, 31 the perforated suction pipe therein, 32 the means for blocking off the segment of the shell which is not sealed by the paper sheet, and 33 the wire cloth jacket on the sheet.

In the specific construction shown, the shell 30 is rigidly attached to heads 131 and 132. The suction pipe 131 has at one end a tubular extension 133 extending through the head 131 and secured in the bearing or support 134. The head 131 is rotatably mounted on the extension 133 by 15 the bearing 135. The suction pipe communicates with the vacuum-pumping apparatus (not shown) through the passage 136 in the support 134 registering with an opening in the suction pipe extension 133 which is closed at its outer end. At its opposite end the suction pipe has a projecting trunnion 137 on which the head 132 is rotatably mounted through the bearing 138. Said head 132 has an extended journal portion 139 journaled on the fixed bearing 140.

As shown in Fig. 9, the suction pipe 31 is constructed with a projecting member of T-shaped cross section comprising the radial web 141 and segmental web 142 connected with the end sector-shaped webs 143 and braced by intermediate sector-shaped webs 144. Attached to the segmental web 142 are side members 145 and segmental end members 146 which are preferably very nearly but not in actual bearing contact with the interior of the perforated shell 30. The construction referred to including especially the web 142 carried by the suction pipe and the side members 145 and end members 146 attached thereto constitute the blocking off means which has been referred to as a whole by the numeral 32.

It is desirable to avoid rubbing contact between the blocking off means and the interior surfaces of the revolving perforated shell, since there would be no adequate means of lubricating these surfaces if in rubbing contact. Hence it is desirable to maintain a slight clearance of from .001" to .003" between the interior surface of the shell and the adjacent surfaces of the members 145 and 146. The members 145 are attached to the flanged or enlarged sides of the segmental web 142 by bolts 147 passing through short slots in said members. Adjusting screws 148 passing through the extensions 149 of the flanged sides of the web 142 bear against the members 145. By adjusting the screws 148 the members 145 may be moved as closely as desired to the inner surface of the rotating shell, and the screws 147 may then be tightened to fasten said members in place. The screws 148 are provided with lock nuts 150. The end members 146 are adjustably secured to the ends of the web 142 by fastening screws 151 passing through short radial slots in said members.

In making newsprint paper, and various other papers having considerable porosity, large volumes of air can be drawn through the paper sheet on the suction driers with the use of a comparatively low vacuum, so that the leakage of air which will take place through the very slight clearances between the members 145, 146 and in- 75

terior of the shell will not be serious, and all friction between the blocking off means and the shell is avoided. However the invention contemplates also a construction in which the side 5 and end members 145 and 146 of the blocking off means are maintained in rubbing contact with the interior of the shell, in which case said members would preferably be of special metal or composition or be provided with packing strips 10 of special metal or composition to reduce the friction.

Within the suction pipe 31 are pipes 152 and 153 connected through valve-controlled connections (not shown) with any suitable source of 15 compressed air, and from which respectively extend the blow-off pipes 154 and 155. The blow-off pipes 154 correspond to the blow-off pipes 11 in Fig. 4, and the blow-off pipes 155 correspond to the pipes 68 in Fig. 3 and 78 in Fig. 4.

20 All of the suction driers may be of the construction described or other suitable construction. The illustrative construction of the suction drier is included as a feature of this invention, but the invention in other aspects is not limited to any 25 specific construction of the suction drier.

Besides eliminating ordinary press and press 30 felt equipment and all the objections incident thereto, the present invention makes possible a very substantial reduction in drying equipment, thus reducing the investment required for machinery, machinery space and buildings and also materially reducing maintenance expense. The 35 majority of the steam traps and about three-fourths of the drier steam joints and siphons required in connection with ordinary drying equipment can be eliminated by the use of the present invention. The paper can be made stronger and of better quality and in greater varieties than by 40 ordinary methods. By controlling the humidity of the paper for calendering, the paper will arrive at the calenders at a more constant condition and will calender with a more uniform finish. By using heat over and over again in the drying 45 apparatus a substantial economy is effected. Due to the heat recovery system, a saving in the power required to produce suction in the suction driers is effected by reason of the condensation of the vapor in the discharged air. The recovery of 50 pure hot water for use over again as white water is highly advantageous, avoiding low temperature which tends to congeal the sizing in the paper when made on a Fourdrinier having ordinary press and drier equipment. As there is no escape 55 of hot vapor into the machine room, the working conditions are much improved for the machine crew. The same condition prevents the condensation of moisture on the ceiling, overhead pipes and the like, and the dripping of dew on the 60 finished paper, thereby preventing damage.

What I claim as my invention, and desire to secure by Letters Patent, is:

1. A paper making machine comprising a wet 65 section on which the paper sheet is made in the wet state, drying equipment to which the wet sheet is delivered from said wet section, said drying equipment comprising a series of drying rolls around which the sheet is carried, certain of said rolls being perforated suction drying rolls 70 having associated means for continuously forcing heated air through substantially the entire area of the sheet entrained on said perforated rolls and the other rolls being heated drying rolls, a press through which the sheet passes after delivery from said drying equipment, and further 75

drying equipment through which the sheet passes after pressing.

2. In paper drying apparatus, a series of driers comprising ordinary driers and suction driers, a housing containing the same, said housing having 5 a warm air inlet, steam coils in said housing for heating the air therein, said coils being arranged in proximity to the suction driers, and coating felts for carrying the paper sheet successively around said driers. 10

3. The improvement in the process of making paper in a continuous sheet which comprises partially drying the sheet before any pressing by drying action involving the carrying of the wet sheet between heated felts and successively forcing large volumes of heated air through the sheet, and thereafter drying the sheet by heating it and successively forcing large volumes of heated air therethrough. 15

4. The improvement in the process of making 20 paper in a continuous sheet which comprises partially drying the sheet before any pressing by drying action which involves carrying the sheet between heated felts while successively forcing large volumes of heated air therethrough, further 25 drying the sheet before any pressing by heating it and successively forcing large volumes of heated air therethrough, and thereafter drying the sheet by heating it and successively forcing large volumes of heated air therethrough. 30

5. The improvement in the process of making 35 paper in a continuous sheet which comprises partially drying the sheet before any pressing by carrying the sheet between heated felts while alternately heating and forcing large volumes of heated air through the felts and interposed paper sheet, further drying the sheet before any pressing by alternately heating the sheet and forcing large volumes of heated air therethrough, and thereafter drying the sheet by drying action involving 40 successively forcing large volumes of heated air through the sheet.

6. The improved method of drying paper in the course of manufacture in a continuous sheet 45 which comprises carrying the wet sheet between heated felts while successively forcing large volumes of heated air through the sheet, and further drying the sheet by alternately heating it and forcing large volumes of heated air therethrough and then by successively forcing large 50 volumes of heated air therethrough.

7. The improved method of drying paper in the course of manufacture in a continuous sheet 55 which comprises carrying the wet sheet between heated felts while alternately heating and forcing large volumes of heated air through the felts and interposed sheet, continuing the drying by heating the sheet and successively forcing large volumes of heated air therethrough, and completing the drying by successively forcing large volumes 60 of heated air through the sheet.

8. A paper making machine comprising a wet section on which the paper sheet is made in the wet state, a press remote from the wet section, drying equipment through which the sheet is passed between said wet section and press, said drying equipment comprising a series of suction drying rolls and heated drying rolls in alternation with suction drying rolls, around which rolls successively the sheet is carried, and drying equipment beyond said press comprising a series of suction drying rolls and heated drying rolls in alternation with suction drying rolls, around 70 which rolls successively the sheet is carried.

9. In a paper making machine, a drying section 75

arranged to receive the wet sheet, said drying section comprising a series of alternately arranged suction drying rolls and heated drying rolls and coacting endless aprons of porous material between which the sheet is carried successively around said driers, a second drying section comprising a series of alternately arranged suction drying rolls and heated drying rolls around which the sheet is successively carried and an endless apron of porous material which

5 passes with the sheet successively around said rolls of said second section, said aprof being outside the sheet on heated drying rolls and inside the sheet on suction drying rolls, and a third drying section comprising a series of driers including heated drying rolls and suction drying rolls around which successively the sheet is carried.

HARRY A. CHUSE.
